INDOOR TELEVISION ANTENNA

Harold J. Berney, Washington, D. C., assignor to Aberney Corporation, Bethesda, Md., a corporation of Maryland

Application June 26, 1953, Serial No. 25,679

Term of patent 14 years

(Cl. D26—14)

FIG. 1

FIG. 2

FIG. 3

FIG. 4

FIG. 5

FIG. 6

To all whom it may concern:

Be it known that I, Harold J. Berney, a citizen of the United States, residing in the District of Columbia, have invented a new, original, and ornamental Design for an Indoor Television Antenna, of which the following is a specification, reference being had to the accompanying drawings, forming part thereof, wherein:

Figure 1 is a front elevational view of an indoor television antenna showing my new design.

Figure 2 is a fragmentary view showing the lower portion of the antenna of Figure 1 in rear elevation.

Figure 3 is a top plan view of the indoor television antenna of Figure 1.

Figure 4 is a horizontal cross sectional view taken through the indoor television antenna on the line 4-4 of Figure 1.

Figure 5 is a horizontal cross sectional view taken through the indoor television antenna on the line 5-5 of Figure 1.

Figure 6 is a bottom plan view of the indoor television antenna of Figure 1.

I claim:

The ornamental design for an indoor television antenna, as shown.
